UNITED STATES PATENT OFFICE.

EZRA W. SAVAGE, OF ASHTABULA, OHIO.

SAP-SPOUT.

SPECIFICATION forming part of Letters Patent No. 224,229, dated February 3, 1880.

Application filed December 13, 1879.

To all whom it may concern:

Be it known that I, EZRA W. SAVAGE, of Ashtabula, in the county of Ashtabula and State of Ohio, have invented a new and Improved Sap-Spout, of which the following is a specification.

Figure 1 is a side elevation of the spout holding a bucket to a tree. Fig. 2 is a plan view of the same. Fig. 3 is a sectional longitudinal elevation of the same on line $x x$, Fig. 2, showing the spout-latch raised. Fig. 4 is a rear end elevation of the spout.

Similar letters of reference indicate corresponding parts.

The object of this invention is to provide a spout by which the sap-bucket may be held to a tree with less injury to the bucket than by any spout now in use.

The invention consists of a latch pivoted to the front end of the spout and a hook formed on the under side, whereby, by the combination of the two, a sap-bucket may be firmly held.

In the drawings, A represents the sap-spout, provided with holes $a a$ for the outflow of the sap in the end that is inserted into the tree, and having on its under side a broad forward-projecting hook, b. On the under side of the spout, near its mouth, is a lug, c, through which the pivot d passes laterally and holds the open stirrup-shaped loop or latch B.

In Fig. 1 the spout A is shown as inserted into a tree, C, and holding a bucket, D, in position by the co-operation of the hook b and

latch B. The curved points f of the latch B 35 facilitate its downward movement over the rim of the bucket D, and the bend or arch g of the latch holds it in the locking position. (Shown in Figs. 1 and 2.)

In ordinary practice a hole is punched in 40 the bucket near the rim, and the bucket is held in position by the spout entering said hole, or the bucket is so constructed that it shall always be suspended at one point from the spout; hence the bucket is quickly broken 45 at such point of attachment, or becomes so much injured as to be useless for the purpose for which it was intended.

With this device the bucket can be held by any part of its rim, so that the wear or strain 50 upon said rim need not be confined to any particular point of it.

Having thus described my invention, I claim as new and desire to secure by Letters Patent

1. As an improved article of manufacture, a sap-spout constructed substantially as herein described, and consisting of spout A, hook b, lug c, and pivoted latch B, as herein set forth.

2. As a means of holding a bucket to a sap-spout, the open stirrup-shaped loop or latch B, in combination with the hook b, substantially as herein shown and described.

EZRA WILSON SAVAGE.
